(57) **CLAIM**

The ornamental design for a rear bumper for automobiles, as shown and described.

DESCRIPTION

FIG. 1 is a front elevational view of a rear bumper for automobiles showing my new design;

FIG. 2 is a left side elevational view thereof, the right side being a mirror image thereof; and,

FIG. 3 is a top, front and left side perspective view thereof. The broken lines in the drawings illustrate portions of the rear bumper for automobiles that forms no part of the claimed design.
